DESIGN FOR A COMBINED CONTAINER AND CLOSURE THEREFOR

Edwin W. Fuerst, Toledo, Ohio

Application September 2, 1933. Serial No. 49,196

Term of patent 14 years

To all whom it may concern:

Be it known that I, EDWIN W. FUERST, a citizen of the United States, residing at Toledo, in the county of Lucas and State of Ohio, have invented a new, original, and ornamental Design for a Combined Container and Closure Therefor, of which the following is a specification, reference being had to the accompanying drawing, forming a part thereof.

In the drawing:

The figure is an elevational view of a combined container and closure thereof showing my design.

I claim:

The ornamental design for a combined container and closure therefor substantially as shown.

Signed at Toledo, in the county of Lucas, and State of Ohio, this 31st day of August, 1933.

EDWIN W. FUERST.
